UNITED STATES PATENT OFFICE.

WALTER H. HIMES, OF PITTSBURGH, PENNSYLVANIA, ASSIGNOR TO WESTINGHOUSE ELECTRIC & MANUFACTURING COMPANY, A CORPORATION OF PENNSYLVANIA.

SHORT-CIRCUITING DEVICE.

Application filed May 11, 1921. Serial No. 468,705.

To all whom it may concern:

Be it known that I, WALTER H. HIMES, a citizen of the United States, and a resident of Pittsburgh, in the county of Allegheny and State of Pennsylvania, have invented a new and useful Improvement in Short-Circuiting Devices, of which the following is a specification.

My invention relates to centrifugally actuated short-circuiting devices for dynamo-electric machines and it has particular relation to single-phase motors of the commutator type that are adapted for repulsion operation during the starting operation and for induction operation after a predetermined speed has been attained.

One object of my invention is to provide simple, effective and inexpensive centrifugally actuated means for operating a short-circuiting device of the above designated character.

Another object of my invention is to provide a centrifugally actuated device provided with a single-weight member so arranged as to be balanced when in its outermost position.

Another object of my invention is to provide contact mechanism of a satisfactory type that shall be adapted to be mounted adjacent to the commutator cylinder, whereby certain segments thereof may be short-circuited.

A still further object of my invention is to provide a mechanism whereby the pressure exerted by the short-circuiting means upon the co-operating contact members shall be maintained substantially constant, irrespective of the speed of the machine, and shall be of sufficient force to insure a good contact therebetween.

Heretofore, it has been customary, in the construction of short-circuiting devices for commutators, to move a short-circuiting member axially into engagement with the ends of the commutator bars. Construction of another type sometimes employed is that in which a disk is moved both axially and rotatably into engagement with the ends of the commutator bars.

My present invention differs from the arrangements previously described in that a disk of insulating material is provided with spaced conducting members imbedded therein which are connected together electrically by an annular conducting member which is

removed, either circumferentially only or longitudinally only, when the machine attains a predetermined speed. Means are provided whereby the pressure on the disk remains constant at all times, thus insuring that a good contact shall be made between the short-circuiting member and the imbedded contact members.

In the accompanying drawings, Figure 1 is a side view, partially in elevation and partially in section, of a commutator cylinder provided with a short-circuiting device constructed in accordance with my invention.

Fig. 2 is an end elevation of the structure shown in Fig. 1, illustrating the centrifugally-actuated weight device employed therein.

Fig. 3 is an end elevational detail view of the rotatable short-circuiting disk as employed in a device constructed in accordance with my invention.

Fig. 4 is a cross-sectional view of a rotor of a dynamo-electric machine illustrating another form which my invention may assume.

Fig. 5 is a cross-sectional view of another modified form of my invention.

In the drawings, I show a commutator cylinder 6 comprising a plurality of insulated circumferentially disposed conducting segments 7 arranged upon, but insulated from, a centrally disposed supporting member 8. The member 8 is, in turn, mounted upon a shaft 9. Upon the end of the commutator cylinder 6 is rigidly mounted a disk 10 composed of insulating material in which are imbedded a plurality of contact members 11. The contact members 11 are each provided with an integral projection 12 of reduced cross-sectional area which extends into, and is electrically and mechanically connected to, one of the commutator segments 7. The outer surfaces 13 of the members 11 are preferably flush with the outer surface of the disk 10.

The contact members 11 are preferably of the ordinary screw type having a threaded body portion 12 of reduced cross-sectional area and a head adapted to be countersunk in an opening provided therefor in the disk 10. The members 11 may, however, consist of pins or rivets having relatively large heads and bodies of reduced cross-sectional areas.

A disk 14, composed of conducting material is rotatably mounted upon the supporting member 8 by means of studs or bolts 15 which extend through arcuate slots 16 in said disk. The disk 14 is also provided with a plurality of spaced resilient contact fingers 17 which are adapted to engage the outer surfaces 13 of the contact members 11 upon being rotated to a suitable position. The 10 disk 14 is also provided with an axially projecting pin 18, the purpose of which will hereinafter be set forth.

The disk 20 is mounted upon the shaft 9 to rotate therewith and is provided with a 15 single centrifugally actuated member 21 pivotally mounted thereon by means of a pin 22. One end of the member 21 is provided with a weighted portion 23 and the other end 24 is attached to a tension spring 25, the opposite 20 end of which is attached to a pin 26 mounted on the disk 20. The member 21 is also provided with an integral offset portion 27 disposed intermediate its ends having inwardly bent flanges 28 which engage the 25 end of the pin 18 which is mounted on the disk 14. The pin 18 extends through an arcuate slot 29 in the disk 20.

The operation of the device is as follows: when the machine is in its starting position, 30 the weight member 23 is in its full-line position, as shown in Fig. 2, and the short-circuiting disk 14 is in the position shown in Fig. 1, that is, with the contact fingers out of engagement with the contact members 11. 35 When the machine attains a predetermined speed, the weight member 21 moves to the position shown in dotted lines in Fig. 2, thus causing the flanges 28 of the portion 27 which engage the pin 18, to rotate the disk 14 to bring the contact fingers 17 into engagement with the contact members 11.

Since the disk 14 moves in a circumferential direction only, and the resilient members 17 are alike, the latter bear upon the 45 disk 10 with equal pressure. Also, the fact that the surfaces 13 of the contact members 11 are flush with the surface of the disk ensures maintenance of constant pressure, even when the contact fingers 17 slide upon such 50 contact faces.

The armature is so balanced that, when the weight 23 is in its innermost or starting position, the rotor is slightly unbalanced, but, when the latter attains a predetermined 55 speed and the weight moves to its outermost position, a balanced condition is attained.

In the structure shown in Fig. 4, a disk 30 is mounted upon a supporting member 31 which, in turn, is mounted upon the shaft of 60 the machine at the opposite end from the commutator cylinder 32. The disk 31 is provided with spaced contact members 33 which are electrically connected to certain of the commutator segments, or to other portions 65 of the windings of the rotor, by means of

connections 34. A rotatable disk 35, provided with contact fingers 36, serves to short circuit the contact members 33, in a manner similar to that pertaining to the device of Fig. 1. Also, a centrifugally-actuated 70 weight member 37, similar to that described in connection with Fig. 1, serves to rotate the disk 35 when the rotor attains a predetermined speed.

Thus, it is seen that, while my structure 75 is particularly adapted to be mounted directly upon the end of the commutator cylinder, nevertheless, it may be mounted upon the opposite end of the machine and connections made to the commutator segments or 80 directly to the winding itself, as may be desired.

In Fig. 5, I show a commutator cylinder in which ends 40 of conducting bars 41 project beyond the end of a centrally disposed 85 supporting structure 42. Upon the inner circumference of the annular member so formed is mounted a ring 43 composed of insulating material. The ring 43 is provided with a plurality of spaced contact members 44, a portion 45 of which projects radially 90 into openings in the ends 40 of certain of the bars 41, establishing electrical contact therewith. The head of the contact member 44 is flush with the surface of the ring 43. An annular conducting member 47 is provided with a plurality of spaced resilient 95 conducting fingers 48 corresponding in number, to the contact members 44 and which engage the heads of the contact members 44 when the ring 47 is moved longitudinally of the commutator cylinder. The member 47 may be moved by means of any centrifugally 100 actuated device, not shown, that is adapted to move a short-circuiting member longitudinally with respect to the commutator cylinder. 105

While I have shown several embodiments of my invention, further changes and modifications may be made without departing 110 from the spirit thereof, and I desire, therefore, that only such limitations shall be placed thereupon as are imposed by the prior art or are specifically set forth in the appended claims. 115

I claim as my invention:

1. In combination with a commutator cylinder, an annular member composed of insulating material and mounted thereon and provided with a plurality of contact members, said contact members being electrically connected to said commutator cylinder, and a relatively movable contact element adapted to engage with said contact members. 120

2. In combination, a commutator cylinder comprising a plurality of conducting segments, a body of insulating material mounted thereon and provided with a plurality of spaced contact members, said contact members being electrically connected to certain 125 130

of said segments spaced about said cylinder, and a relatively rotatable member having contact brushes adapted to move in and out of engagement with said contact members.

5 3. In combination with a commutator cylinder, an annular member composed of insulating material mounted thereon and provided with a plurality of contact members, said contact members being electrically connected to said commutator cylinder, and means actuated by centrifugal force for engaging and short-circuiting said contact members.

15 4. In combination, a commutator cylinder comprising a plurality of conducting segments, an insulating annular member mounted adjacent to the end of said cylinder, said annular member being provided with contact members imbedded therein, a portion of each of said contact members extending into an opening in one of said segments and being attached thereto, and a relatively rotatable member having short-circuited contact brushes adapted to engage 25 said embedded contact members in one position.

5. In combination, a commutator cylinder comprising a plurality of conducting segments, an insulating disk mounted in engagement with the end of said cylinder, said disk being provided with contact members imbedded therein, the surface of said contact members being substantially flush with the surface of said disk, each of said contact members being provided with an integral portion extending into, and attached to, one of said commutator segments, and a relatively rotatable contact element adapted to engage with said contact members.

40 6. In a dynamo-electric machine, a commutator cylinder comprising a plurality of conducting segments, an insulating annular member mounted in engagement with the end of said cylinder, said annular member being provided with contact members imbedded therein, the surface of said contact members being substantially flush with the surface of said annular member, each of said contact members comprising a threaded portion 45 extending into an opening in one of said commutator segments and a head portion imbedded in said annular member, and a relatively rotatable short-circuiting member having brushes adapted to move into and out of engagement with said contact members.

55 7. In combination, a shaft, a supporting structure thereon, a commutator cylinder mounted upon said supporting structure and comprising a plurality of conducting segments, an insulating disk mounted in engagement with the end of said cylinder, said disk being provided with contact members imbedded therein, said contact members being substantially flush with a surface of said disk, each of said contact members be-

ing provided with an integral portion extending into, and attached to, one of said segments, a relatively movable disk composed of conducting material mounted adjacent to said first mentioned disk and provided with resilient contact fingers adapted to engage said contact members upon rotation of said last mentioned disk, said last mentioned disk being rotatably mounted upon said commutator-cylinder-supporting structure.

80 8. A speed responsive device comprising a shaft, a relatively rotatably mounted ring-member thereon and a centrifugal device for operating the same, comprising an arcuate-shaped lever-member having a pivot pin intermediate its ends and carrying an abutment pin spaced substantially radially from said pivot pin, one of said pins being carried by said shaft and the other by said ring-member, a weight on one end of said lever-member, a spring having one end attached to the other end of said lever-member, and a support for the other end of said spring, said support being carried by the same element which carries said pivot pin.

85 9. In a dynamo-electric machine, a rotor, a disk composed of insulating material mounted on said rotor, a plurality of contact members imbedded therein, the surface of said contact members being substantially flush with the surface of said disk, and means adapted to engage said contact members when said rotor attains a predetermined speed.

90 10. In a dynamo-electric machine, a rotor, a disk composed of insulating material mounted on said rotor, a plurality of contact members imbedded therein, the surface of said contact members being substantially flush with the surface of said disk, a second relatively rotatable disk mounted adjacent to said first mentioned disk and provided with a plurality of resilient contact fingers adapted to engage said contact members upon angular movement of said last mentioned disk, and means for actuating said last mentioned disk when said rotor attains a predetermined speed.

100 11. In combination, a commutator cylinder comprising a plurality of conducting segments, an annular member composed of insulating material and mounted adjacent to the end of said cylinder, said annular member being provided with contact members imbedded therein, each of said contact members being provided with a reduced portion extending into, and attached to, one of said commutator segments, and a relatively movable contact element adapted to contact with said contact members.

115 12. In a dynamo-electric machine, a disk composed of insulating material and having a plurality of contact members embedded therein, the outer surface of said contact

members being substantially flush with the surface of said disk, a relatively rotatably mounted member disposed adjacent to said disk and provided with contact fingers 5 adapted to engage said contact members when said rotatable member is moved, and centrifugally actuated weights connected to

said rotatable disk by means of a pin-and-slot connection.

In testimony whereof, I have hereunto 10 subscribed my name this 21st day of April, 1921.

WALTER H. HIMES.
